APPARATUS FOR MAKING NETS

George W. Hanson, San Francisco, Calif.

Application November 24, 1936, Serial No. 112,518

7 Claims. (Cl. 140—11)

This invention relates to an apparatus for making nets or the like.

The general concept of the invention is to provide an apparatus whereby intersecting groups of suitable lines, such as cords, can be quickly moved into desirable spaced positions so as to be supported at their selected points of intersection, to facilitate the fastening together of the cords at their points of intersection.

10 Another object of this invention is to provide an apparatus wherein a set of cords or the like, running in one direction, are supported in spaced elements, and another set of cords are drawn in intersecting relation to the first set of cords and placed on said spaced elements for quick fastening of a large number of intersecting points of the cords of a net, means being provided for definitely spacing the fastened cords removed from said supports so that the subsequent fastenings are in a predetermined relation to the previously finished fastenings, thereby permitting quick and easy handling and fastening of the intersecting cords of a net in larger groups.

20 A further object of the invention is to provide an apparatus for making nets of the type above referred to which is simple in construction, efficient in operation, durable in use and capable of manufacture on a commercial scale.

In this specification and the annexed drawing, the invention is illustrated in the form considered to be the best, but it is to be understood that the invention is not limited to such form, because it may be embodied in other forms; and it is also to be understood that in and by the 35 claims following the description, it is desired to cover the invention in whatsoever form it may be embodied.

In the accompanying drawing:

Fig. 1 is a plan view of the apparatus.

40 Fig. 2 is a somewhat diagrammatic plan view of an end of the apparatus, the arrows indicating the direction of progress of the cords.

Fig. 3 is a sectional view of the apparatus, the section being taken on the line 3—3 of Fig. 2.

45 Fig. 4 is a somewhat diagrammatic side view of the apparatus.

Fig. 5 is one of the dies shown in plan view.

Fig. 5a is a side elevation of Fig. 5.

Fig. 5b is an end elevation of Fig. 5.

50 Fig. 6 is a side view fastened joint of the net.

Fig. 6a is a plan view of Fig. 6.

Fig. 7 is a sectional view showing the relative position of the cords at a point of intersection.

Fig. 8 is a plan view of one of the joiner cups.

55 Fig. 8a is a side elevation of the upper cup.

Fig. 8b is a side elevation of the lower cup.

In general my apparatus includes the steps of supporting the cords of the net running substantially in the same direction, at suitably spaced points of each cord. The said points of support are so located as to correspond to the points of intersection where the crossing cords of a net are fastened together. Then other cords are pulled below the plane of the first cords so that the second set of cords are disposed at a desired angle to the first set of cords. It is preferable that one end of each of the second set of cords be fastened so as to be held stationary and then each cord be so pulled off from a usual reel or the like that each cord is pulled in a double strand. The points of support of the first set of cords are located in rows, and the second set of cords is pulled parallel with said rows of supporting points so that a double strand is positioned between each pair of adjacent rows of supporting points. Then the pulled or doubled ends of said strands are cut and each strand of each cord is lifted onto the nearest row of said points of support. Then the intersecting cords are fastened together at each point of support. After a comparatively large section of the net is thus formed, the same is moved into an out of way position by advancing the first set of cords from said points of support so that the last row of fastened intersections of the completed portion of the net is at a definitely determined distance from the first adjacent row of support points, which distance is equal to the spacings between the rows of supporting points when the joints of the net are equidistant from each other. Thereafter the second set of cords is again pulled from its rolls or reels between said rows of support points and the operation is repeated until a net of a desired size is completed.

In carrying out my invention I prefer to use separable fasteners such as complementary metal cups of the type shown in Fig. 8. Each fastener is made of two complementary cups 11. Each cup 11 is so formed that it has intersecting channels 12 and 13 of semi-circular cross section, at right angles to each other. The middle portion of each cup 11 is bulged outwardly so as to provide a dip 14 in said channels 12 and 13, so that the intersecting portions of cords 15 and 16 can be held in the cup in superimposed relation as shown in Fig. 7. One cup 11 faces upward and after the cords 15 and 16 are in place thereon, another cup 11 is pressed over it in inverted position. The edges of the complementary cups 11 are adapted to interlock when pressed to

gether so as to form a firm fastening of the intersections. The portions of the cords thus pressed into the bulges 14 are prevented from sliding or moving relatively to each other.

5 My apparatus for applying fasteners to the cords includes a frame 17 of any desirable length and width. The frame 17 has a plurality of spaced supports 18 arranged to correspond to the spacing of the joints of the net to be made. In 10 this illustration, the joints of the net are equidistant from each other. The supports 18 are aligned in longitudinal rows on the frame. On the top of each support 18 is suitably fixed a die 19. Each die 19 has a hollow receptacle 21 15 formed in its top to firmly fit the convex side of a cup 11 in such manner that the channels 12 and 13 are in registry with the respective channels 12 and 13 of the cups 11 in the other receptacles 21.

20 In the herein description the set of cords 15 which extends across the narrower portion of the frame 17 will be referred to as transverse cords 15, and the set of cords 16 which extends the length of the frame 17 will be referred to as 25 longitudinal cords 16. Both cords may be made of any suitable material, such as rope or wire or the like.

The transverse cords 15 are fed across the frame 17 in the manner shown in Fig. 3. It is preferable that each cord 15 be unrolled from a suitable roll of cord. The longitudinal cords 16 are also unrolled from rolls or reels 22 shown in Fig. 4, but before unrolling, an end of each cord 16 is tied fast to a stationary element relatively 35 to an end 23 of the frame 17. Each half loop 24 thus formed is placed loosely in the groove of a pulley 26. Each pulley 26 in turn travels in a longitudinal guide recess 27 in the frame 17, below the level of the dies 19. The shaft 28 of 40 each pulley 26 moves in a longitudinal slot 29 in the bottom of the recess 27 and is connected to an endless conveyor line 31, which latter is moved around suitable rollers 32. By pulling the conveyor line 31 the pulley 26 connected 45 thereto, can be drawn from the end 23 to the other end 33 of the frame 17. Thus the doubled portion of each longitudinal cord 16 is pulled across and below the transverse cords 15 from one end to the other end of the set of cords 15.

50 In operation first a lower cup 11 of the fasteners is placed into each receiver 21 of each die 19. Then the transverse cords 15 are placed into the aligned channels 12 of the cups 11. Then the longitudinal cords 16 are pulled in place as heretofore described and each cord 16 is cut at the pulley 26 and at the tied and roll ends. Each branch or strand is then lifted to the adjacent row of dies 19 and is placed into the aligned channels 13 of the respective cups 11 below the 55 cords 15, so that the respective cords 15 and 16 are in intersecting and contacting position at their points of intersection. It is to be noted that one of the strands of one of the longitudinal cords 16 is left over in each operation and it is used in the next operation. Lastly, an inverted 60 upper cup 11 is hammered or pressed down onto the joint on each lower cup 11 so as to fasten each intersection together as shown in Fig. 6. As a section of the net is thus completed it is 65 removed from the dies 19 in the direction indicated by the arrows along the cords 15.

In order to assure a predetermined spacing of all the joints of the net, the completed portion of the net is drawn over the downwardly inclined frame members 34. The completed net 75

is kept in extended position by a guide bar 36 secured to the inclined frame members 34 so as to lie parallel with the longitudinal edge of the frame 17. The bar 36 is provided with slots 37 so that the transverse guides 15 are guided in spaced relation as the completed portion of the net is removed from the top of the frame 17. The guide bar 36 is spaced from the adjacent row of dies 19 the same distance as the distance between the dies 19. The slots 37 are 10 smaller than the joint cups 11 so that the movement of the completed portion of the net, when removed from the top of the frame 17, is intermittent. As the last joints of the completed portion of the net abut against the guide bar 37, 15 the remaining portions of the cords 15 lie in the proper position on the dies 19, for the proper spacing of the next portion of the net to be joined. At this time the longitudinal cords 16 are pulled along the guide rows 27 from one end 20 of the set of cords 15 to the other as heretofore set forth, and the joining operation is repeated as heretofore described.

By the use of my apparatus, the individual knotting and joining of intersecting cords for the 25 net is obviated because in my apparatus any selected large number of intersecting cords may be quickly and easily set in place, and then readily joined in properly aligned dies so as to form a 30 regularly and equally spaced net of any length or width.

Having thus described this invention, what I claim and desire to secure by Letters Patent is:

1. In an apparatus for joining intersecting cords by means of complementary joiner cups to 35 form a net or the like; a plurality of dies each being adapted to hold a joiner cup therein; means to support said dies in groups in spaced positions, so aligned that a cord can be laid upon the cups in each group of dies; means to feed a plurality of 40 cords below the level of the first cords and crosswise relatively to the first cords so as to permit the placing of said second cords into the respective cups below the respective first cords at their points of intersection; and means whereby an 45 inverted upper cup can be pressed into union with each of said lower cups in the dies so as to hold said cords together at their points of intersection.

2. In an apparatus for joining intersecting 50 cords by means of complementary joiner cups to form a net or the like; a plurality of dies each being adapted to hold a joiner cup therein; means to support said dies in groups in spaced positions, so aligned that a cord can be laid upon the 55 cups in each group of dies; means to feed a plurality of cords below the level of the first cords and crosswise relatively to the first cords so as to permit the placing of said second cords into the respective cups below the respective first cords at their 60 points of intersection; and means whereby an inverted upper cup can be pressed into union with each of said lower cups in the dies so as to hold said cords together at their points of intersection; and guiding means for the 65 first set of cords so coacting with said joined cups as to intermittently stop and space said first set of cords in a predetermined relation to said group of dies.

3. In an apparatus for making nets or the like 70 by applying fastening elements to the intersections of sets of cords; a frame; a plurality of holders on the frame for said fastening elements, one set of said cords being fed directly over said holders and elements; and means below the level 75

of said members for feeding the other intersecting set of cords across from one end to the other end of the first set of cords, so as to permit the lifting of the cords of said second set onto said fastening elements in the respective holders.

5. In an apparatus for making nets or the like by applying fastening elements to the intersections of sets of cords; a frame; a plurality of holders on the frame for said fastening elements, one set of said cords being fed directly over said holders and elements; means below the level of said members for feeding the other, intersecting set of cords across from one end to the other end of the first set of cords, so as to permit the lifting 10 of the cords of said second set onto said fastening elements in the respective holders; and spacing means on said frame coacting with the fastened intersections on the first set of cords to determine the spaced position of the first set of cords on said holders relatively to the points of the first set of cords to which the fasteners were previously applied.

6. In an apparatus for making nets or the like by applying fastener elements to the intersections 25 of sets of cords; a frame; transverse rows of holders for said fastening elements spaced on the frame; a plurality of longitudinal runways between the holders on the frame; a traveling member movable longitudinally on each runway, each traveling member carrying extended cords longitudinally to said frame so that said longitudinal cords can be placed onto the respective holders in intersecting relation to the transverse cords; and means to move said traveling members.

30 35 6. In an apparatus for making nets or the like by applying fastener elements to the intersections

of sets of cords; a frame; transverse rows of holders for said fastener elements spaced on the frame; a plurality of longitudinal runways between the holders on the frame; a traveling member movable longitudinally on each runway, each 5 traveling member carrying extended cords longitudinally to said frame so that said longitudinal cords can be placed onto the respective holders in intersecting relation to the transverse cords; and means to move said traveling members, each 10 traveling member being adapted to have a longitudinal cord placed around it with an end of each longitudinal cord being held stationary so that each traveling member feeds two lines at a time, one line for each set of holders on each side 15 of the runway.

7. In an apparatus for making nets or the like by applying fastener elements to the intersections of sets of cords; a frame; transverse rows of holders for said fastening elements spaced on the 20 frame; a plurality of longitudinal runways between the holders on the frame; a traveling member movable longitudinally on each runway, each traveling member carrying extended cords longitudinally to said frame so that said longitudinal 25 cords can be placed onto the respective holders in intersecting relation to the transverse cords; means to move said traveling members; and a guide related to the frame, extending longitudinally of the frame, to guide said transverse cords 30 when moved across and off the holders, said guide being adapted to engage fastened points of intersection on said transverse cords so as to determine the spacing of the last completed fastened points of intersection from said holders. 35

GEORGE W. HANSON.
